LIP BRUSH HOLDER WITH MANUAL
RELEASE AND GRAVITY DROPDon Gordon, Burbank, Calif., assignor to
E. Manuel Stolaroff, Los Angeles, Calif.

Application December 30, 1946, Serial No. 719,296

10 Claims. (Cl. 15—184)

1

The present invention relates to retractable implement holders, and more particularly to retractable lip brush holders in which the brush can be withdrawn into a casing so that it may be carried in a hand bag without soiling the contents thereof and without picking up particles of lint, dust, or tobacco crumbs on the brush hairs from the interior of the bag. While the holder of the present invention was designed specifically for lip brushes, it is also contemplated that it might be used to contain any other tool which might be carried in a hand bag or pocket, such as screw drivers, knives, fountain pens, and the like. Accordingly, the expression "lip brush holder" is not to be taken as restricted solely to that one implement, but instead, includes other tools and devices such as those mentioned above.

One of the principal objects of the invention is to provide a retractable lip brush holder which is convenient and easy to use, and which can be manipulated with one hand.

Another object of the invention is to provide a retractable lip brush holder which is simple and inexpensive to manufacture and which is, at the same time, compact and attractive in appearance.

A further object of the invention is to provide a holder of the class described in which the lip brush carrier is moved by gravity between extended and retracted positions, thereby doing away with the usual spiral slots, sliding buttons, and other devices which have heretofore been utilized to effect extension or retraction of the lip brush.

Still another object of the invention is to provide a lip brush holder in which the brush carrier is released and permitted to move out to extended position or to retract back into the casing by merely depressing a button in the end of the holder.

The foregoing objects are achieved in the present invention by providing a hollow casing which is open at one end, and a lip brush carrier which is freely slideable within said casing between a retracted position wholly contained within the casing, and an extended position wherein the brush is projected through the open end of the casing.

A closure is provided for the open end of the casing which may, as in the preferred form shown, comprise two or more opposed spring strips held at one end by the casing. The free ends of the spring strips are bent inwardly toward one another and terminate in lips which are normally closed together above the brush. A sleeve member which is slideably disposed within the casing

is engageable at one end with the free end portions of the spring strips to spread the latter and permit the brush carrier to drop out by gravity to extended position, or to retract by gravity back into the casing.

The above and other objects and advantages of the invention will become apparent to those skilled in the art upon consideration of the following detailed description of the preferred embodiment thereof, reference being had to the accompanying drawings in which:

Figure 1 is a longitudinal median section taken through a lip brush holder embodying the principles of the invention, showing the brush retracted;

Figure 2 is a plan view of the open end of the holder;

Figure 3 is a sectional view through the holder taken at 90° to the section of Figure 1;

Figure 4 is a view showing the brush in extended position;

Figure 5 is an enlarged sectional view taken along the line 5—5 in Figure 1;

Figure 6 is a perspective view drawn to enlarged scale of one of the closure spring strips;

Figure 7 is a sectional view of another embodiment of the invention;

Figure 8 is an end view of the same; and

Figure 9 is a perspective view of one the spring segments forming the closure for the open end of the casing.

The preferred form of the invention illustrated in Figures 1 to 6, inclusive, comprises a generally cylindrical casing 10 of either metal or plastic, having a central bore 11 extending through one end thereof. At its bottom or open end, the casing 10 is reduced in diameter to form a necked-down portion 12 which receives a tubular end piece 13 having a rounded outer end 14 slotted transversely at 15. Slidably disposed within the bore 11 is a sleeve 16 having a plug 20 inserted into the top end thereof. A button 21 projects axially from the top end of the plug 20 and extends through a bore 22 in the end of the casing.

An implement carrier, hereinafter referred to as the lip brush carrier, is designated in its entirety by the reference numeral 23, and is slidably disposed within the sleeve 16. The carrier 23 comprises a piston 24 having a stem 25 of reduced diameter projecting downwardly from the bottom end thereof to form a shoulder at 26. Formed in the stem 25 and spaced downwardly from the shoulder 26 is an annular groove 27, the purpose of which will appear presently. Be-

low the groove 27, the stem 25 is reduced in diameter to form a stud 28 which receives the top end of a sheet metal ferrule 30 holding the hairs 31 of a brush. At its bottom end, the sleeve 16 is cut away at opposite sides, leaving two laterally spaced, axially projecting lugs 32 which extend down into the slot 15 in the end of the casing. The lugs 32 are made somewhat thicker than the cylindrical wall portion of the sleeve 16, forming an internal shoulder 33 which is engageable by the shoulder 26 when the carrier is moved out to the extended position shown in Figure 4, to limit the outward movement of the carrier and prevent the latter from dropping entirely out of the casing.

Closure means are provided for the open end of the casing comprising in the preferred form, a pair of opposed spring strips 35 having straight portions 36 which are arranged parallel to the axis of the casing. Near their ends, the straight portions 36 of the spring strips are pierced by holes 37 which are adapted to receive bosses 38 projecting radially outward from the necked-down portion 12 on opposite sides thereof. Two diametrically opposed, axially extending grooves 39 are broached or otherwise formed in the inside surface of the tubular member 13, and the straight portions 36 of the spring strips are confined within the space between the bottoms of the grooves and the neck 12, being anchored in place by the bosses 38. The outer end portions of the spring strip 35 are disposed within the slot 15 in the casing and are bowed in toward one another at 40, terminating in rolled lips 41 which are normally closed together, as shown in Figures 1 and 2. The bottom of the slot 15 terminates just above the beginning of the bowed portion 40, so that the side walls of the member 13 provide solid backing for the spring strips 35. Hence, when the strips are bent back, the bending takes place in the bowed portion 40 just below the end of the member 13. The bottom edge of the member 13 is rounded off at 42 so as to provide a gradual radius of bend for the strips.

The bottom ends of the lugs 32 are engageable with the under sides of the bowed portions 40 of the spring strips 35 when the sleeve 16 is pressed downwardly, to spread the lips 41 apart, thereby permitting the lip brush carrier 23 to drop out to extended position by gravity when the casing is held with the open end down. The carrier is stopped in its downward travel by engagement of the shoulder 26 on the carrier with shoulder 33 on the inside of the sleeve. When the button 21 is released, the spring strips 35 close together, seating the lips 41 in the annular groove 27 in the stem 25. To this end, the distance from the shoulder 26 to the top edge of the groove 27 is made substantially the same as the length of the lugs 32 so that the groove is positioned just below the ends of the lugs when the carrier is extended, and therefore exposed to engagement by the lips 41. The engagement of the spring strips with the groove 27 holds the brush carrier out in extended position and prevents it from dropping back into the casing when the holder is turned so that the open end is up.

To retract the carrier back into the casing, the holder is held so that the open end is up, and the button 21 is then pressed inwardly, causing the lugs 32 on the sleeve 16 to lift the spring strips out of the groove 27 and permit the carrier to drop by gravity back into the casing. The button is then released and the spring strips 35 close together. Alternatively, the carrier may

be retracted by holding the casing with the brush end up and then tapping or pressing the button against a table top or other object.

In the second embodiment of the invention, illustrated in Figures 7, 8 and 9, the open end of the casing is closed by a dome-shaped rosette 50 comprising a plurality of spring segments 51 arranged in a circle and having their outer ends bent inwardly so as to converge on the axis of the casing. Each of the spring segments 51 is preferably formed of steel strip and is provided with a straight portion 52 which is curved cylindrically so as to fit against the neck 12, and an outer end portion 53. The end portion 53 is flat and generally triangular in shape, and is bent inwardly toward the center of the casing, terminating in a tip 54 which is bent to lie in a plane perpendicular to the axis of the casing. The spring segments 51 are assembled on the neck 12 with their tip ends converging on the axis of the holder, and are clamped to the neck by a circular band 55 which is slipped down over the straight portions 52 of the assembled segments. The inside diameter of the band 55 is made to provide a snug fit over the spring segments 51, and the height or length of the band is substantially the same as the length of the straight portions 52.

The rosette 50 is opened to permit the brush carrier 23 to move out to extended position by bending the end portions 53 of all of the spring segments outwardly, and sleeve 16 is therefore not cut away on opposite sides, as in the preceding embodiment, but instead is left cylindrical to the end. Thus, when the button 21 is pressed inwardly, the opposite end of the sleeve 16 engages the end portions 53 of the spring segments, bending them outwardly and spreading the tip ends 54 apart as shown in dot-dash lines in Figure 7 to permit the brush carrier to drop out by gravity to extended position. When the button 21 is released, the ends 54 seat in the groove 27 to lock the carrier in place. The lip brush carrier may then be released and permitted to drop back into the casing by again depressing the button 21, which causes the sleeve 16 to bend the spring segments 51 outwardly until the ends 54 are lifted out of the groove 27.

The invention also contemplates that the rosette 50 might be made in one piece from a length of tubing, the end of which is notched to leave triangular points which are then bent inwardly to form the dome-shaped rosette. In this case, the cylindrical tubular portion could be made to fit tightly on the neck 12 so that the band 55 might be dispensed with. In another alternative form, the rosette 50 might be blanked out of flat sheet metal stock to form a strip having a saw-toothed contour along one edge thereof. The points of the strip would then be bent to the desired angle in a forming operation, and the strip then bent or rolled to cylindrical shape to fit over the neck 12. A tightly fitting band such as the one designated 55 at 55 in Figure 7 would be inserted over the rolled strip to hold the latter on the neck 12.

Among the advantages of my improved lip brush holder are its simplicity, compactness and ease of operation. When the brush is retracted into the casing, the holder may be carried in a hand bag without fear of soiling the contents thereof and without picking up dirt, lint, or particles of tobacco on the brush hairs.

While I have shown and described in detail what I consider to be the preferred forms of my

Invention, it is to be understood that the embodiments shown are merely illustrative and that various changes may be made without departing from the scope of the broad claims appended hereto.

I claim:

1. A holder for lip brushes and the like comprising a hollow casing open at one end, a carrier slidably disposed within said casing for movement between a retracted position wholly contained within the casing and an extended position wherein one end of the carrier projects from the open end of the casing, closure means for said open end of the casing comprising a pair of opposed spring strips, each of said strips being held at one end by said casing, and the free ends of said strips being movable between a normally closed position in contact with one another and a flexed open position wherein said ends are elastically bent apart, and means independent of said carrier for bending apart said free ends of the spring strips to permit said carrier to drop out to extended position.

2. A holder for lip brushes and the like comprising a hollow casing open at one end, a carrier slidably disposed within said casing for movement between a retracted position wholly contained within the casing and an extended position wherein one end of the carrier projects from the open end of the casing, closure means for said open end of the casing comprising a pair of laterally spaced, opposed spring strips, each of said strips being formed with a straight portion disposed parallel to the axis of said casing and an inwardly bent outer end portion terminating in a lip, said lips being normally contiguous to close said open end of the casing, and said straight portions of the strips being confined by the casing, and means independent of said carrier engageable with the outer end portions of said spring strips for spreading the same apart to permit said carrier to drop out to extended position.

3. A holder for lip brushes and the like comprising a casing formed with a cylindrical bore extending through one end thereof, a sleeve member slidably disposed within said bore, a carrier slidable within said sleeve member and movable between an enclosed position wholly contained within the casing and an extended position wherein one end of the carrier projects from the open end of the casing, closure means for said open end of the casing comprising a pair of laterally spaced, opposed spring strips arranged parallel to the axis of said casing on the outside of said sleeve member, the outer ends of said strips being bent inwardly and terminating in lips which are normally contiguous to close the open end of said bore, said outer end portions of the strips being engageable by the end of said sleeve member to spread said lips and thereby permit said carrier to move out to extended position, and manually operable means for moving said sleeve member within said casing to engage said strips.

4. A holder for lip brushes and the like comprising a casing formed with a cylindrical bore extending through one end thereof, a sleeve member slidably disposed within said bore, a carrier slidable within said sleeve member and movable between an enclosed position wholly contained within the casing and an extended position wherein one end of the carrier projects from the open end of the casing, said carrier having an annular groove formed therein, clo-

sure means for said open end of the casing comprising a pair of laterally spaced, opposed spring strips arranged parallel to the axis of said casing on the outside of said sleeve member, the outer ends of said strips being bent inwardly and terminating in lips which are normally contiguous to close the open end of said bore, said lips being adapted to seat within the annular groove in said carrier to lock the latter in extended position, said outer end portions of the strips being engageable by the end of said sleeve member to spread said lips so as to open said bore to permit said carrier to move out to extended position, or to lift said lips out of said annular groove to permit said carrier to return to enclosed position, and means for moving said sleeve member within said casing to engage said strips.

5. A holder for lip brushes and the like comprising a casing formed with a cylindrical bore extending through one end thereof, a sleeve member slidably disposed within said bore, a carrier slidable within said sleeve member and movable between an enclosed position wholly contained within the casing and an extended position wherein one end of the carrier projects from the open end of the casing, closure means for said open end of the casing comprising a pair of laterally spaced, opposed spring strips arranged parallel to the axis of said casing on the outside of said sleeve member, the outer ends of said strips being bent inwardly and having lips which are normally contiguous to close the open end of said bore, said outer end portions of the strips being engageable by one end of said sleeve member to spread said lips and thereby permit said carrier to move out to extended position, and a push button fixed to the other end of said sleeve member and projecting axially through the end of said casing opposite said closure means, whereby said closure means may be opened by pressing on said push button.

6. A holder for lip brushes or the like comprising a hollow casing open at one end, a carrier slidably disposed within said casing for movement between a retracted position wholly contained within the casing and an extended position wherein the carrier projects from the open end thereof, closure means for said open end of the casing comprising a plurality of spring elements arranged around the periphery of the casing and extending inwardly so that their tip ends converge centrally and form a closure in the normal unflexed position of said elements, and manually operated means independent of said carrier for elastically bending said spring elements outwardly to permit said carrier to drop out to extended position.

7. A holder for lip brushes or the like comprising a hollow casing open at one end, a carrier slidably disposed within said casing for movement between a retracted position wholly contained within the casing and an extended position wherein the carrier projects from the open end thereof, a closure for said open end of the casing comprising a plurality of spring elements arranged around the periphery of the casing and having pointed end portions converging inwardly to the axis of the casing, and a sleeve slidably disposed within said casing and engageable with the inside surface of said spring elements for elastically bending the latter outwardly, thereby permitting said carrier to move out to extended position.

8. A holder for lip brushes or the like com-

prising a hollow casing open at one end, a carrier disposed within said sleeve and movable between a retracted position wholly contained within the casing and an extended position wherein the carrier projects from the open end thereof, a plurality of spring segments arranged around the outside of said casing at the open end thereof, each of said spring segments being formed with a straight portion disposed to lie against the outside surface of said casing and an end portion extending inwardly toward the axis of the casing, a band embracing the straight portions of said segments to clamp the latter to the casing, and means independent of said carrier for engaging the end portions of said segments and elastically bending the same outwardly whereby said carrier is permitted to move out to extended position.

9. A holder for lip brushes or the like comprising a cylindrical casing having a central bore extending through one end thereof, a sleeve slideable axially within said bore, a carrier disposed within said sleeve and movable between a retracted position wholly contained within the casing and an extended position wherein the carrier projects from the open end thereof, a plurality of spring segments arranged around the periphery of said casing at the open end thereof, each of said spring segments being formed with a straight portion curved cylindrically to lie against the outside surface of said casing and a triangularly shaped end portion bent inwardly so that its apex lies on the axis of the casing, and a band embracing the straight portions of said segments to clamp the latter to the casing, said

sleeve being engageable with the under side of said end portions of the spring segments to elastically bend the same outwardly whereby said carrier is permitted to move out to extended position.

10. A holder for lip brushes and the like comprising a hollow casing open at one end, a carrier slidably disposed within said casing for movement between a retracted position wholly contained within the casing and an extended position wherein one end of the carrier projects from the open end of the casing, closure means for said open end of the casing comprising a plurality of opposed flexible spring strips, each having a shank confined by and fixedly secured to the casing and an inwardly bent outer end portion, said outer end portions converging toward one another to form a closure for the open end of the casing when in their normal positions, and means independent of said carrier engageable with the outer end portions of said spring strips for bending the same apart to permit said carrier to drop out to extended position.

DON GORDON.
